UNITED STATES PATENT OFFICE.

JOSEPH MAYER, OF SEATTLE, WASHINGTON.

DESIGN FOR A WATCH-FOB OR SIMILAR ARTICLE.

• 41,980.

Specification for Design.

Patented Dec. 19, 1911.

Application filed August 21, 1911. Serial No. 645,297. Term of patent 3½ years.

To all whom it may concern:

Be it known that I, JOSEPH MAYER, a citizen of the United States, residing at Seattle, King county, Washington, have invented a new, original, and ornamental Design for a Watch-Fob or Similar Article, of which the following is a specification, reference being had to the accompanying drawing, forming part thereof.

The figure is a plan view of a watch fob or similar article, showing my new design.

I claim:

The ornamental design for a watch fob or similar article, as shown.

JOSEPH MAYER.

Witnesses:

FANNIE WHITE,
B. A. PHILLIPS.
